UNITED STATES PATENT OFFICE.

MASON A. BAMBOROUGH AND HAROLD A. BAMBOROUGH, OF CHICAGO, ILLINOIS.

ELECTRIC-LIGHT GLOBE.

Application filed June 18, 1923. Serial No. 645,975.

To all whom it may concern:

Be it known that we, MASON A. BAMBOROUGH and HAROLD A. BAMBOROUGH, both citizens of the United States, and residents of Chicago, Cook County, Illinois, have invented certain new and useful Improvements in Electric-Light Globes, of which the following is declared to be a full, clear, and exact description.

This invention relates to electric light globes, and its principal object is to provide a globe of improved construction and having a novel shape whereby it may be formed of very thin material throughout, and whereby a maximum efficiency may be obtained from the lamp contained in the globe. Another object is to eliminate bright spots and dark spots in the globe and to provide one in which the light, issuing from the lamp, is diffused in all directions whereby a soft mellow and bright light may be obtained. With these and other objects and advantages in view, this invention consists in an electric light globe, the side wall of which takes the form, in vertical, cross section, of double reverse curves, whereby annular, outwardly bulged portions are formed adjacent the upper and lower portions of the globe, the upper bulged portion being approximately directly over the lower bulged portion, and an inwardly bulged portion intermediate said outwardly bulged portions. The invention further consists in the several novel features hereinafter fully set forth and claimed.

The invention is clearly illustrated in the drawing accompanying this specification, in which:

Fig. 1 is a perspective view, looking from below, of an electric light globe embodying a simple form of the present invention; Fig. 2 is a central, vertical section through the globe and showing in side elevation, a shade holder, an electric light socket, and an electric lamp, and Fig. 3 is a detail, horizontal section taken on the line 3—3 of Fig. 2.

Referring to said drawing, which illustrates a simple embodiment of the present invention, the globe A, is shown as secured to and supported by a holder B, of common and well known construction, having the usual set screws b, for engagement with the neck a, of the globe. In the form shown, the holder B, is clamped upon an electric light socket C, by a suitable clamp, as is

well understood, and an electric lamp D, of the incandescent type is secured in the socket C and projects down into the interior of the globe. In order to obtain a brilliant light, it is preferred to use an incandescent electric light lamp of the "nitrogen" type, although, of course, this is not essential to the invention, broadly considered.

The shape of the walls of the globe is best seen in Fig. 2 where it will be seen that the side wall a¹, in vertical section takes the shape of a double reverse curve which merges into the bottom wall a² of the globe. The double reverse curve forms upper and lower outwardly bulged annular portions 4, 5, and an inwardly bulged portion 6 intermediate the outwardly bulged portions 4, 5. The upper and lower bulged portions are approximately in vertical alignment. The outwardly bulged portion 4 curves upwards and inwards towards the center of the globe, as at 7, forming the top which merges into the flaring neck a. The lower outwardly bulged portion 5 merges into a curved portion 8 which curves downward and inward towards the center of the globe and then curves downward, as at 9, finally merging into a reverse curve 10 which continues on towards the other side of the globe, and the curved lines just described continue throughout the entire top wall, side wall and bottom wall of the globe. It will be noted that the outwardly bulged portion 5 of the globe is of slightly less diameter than the outwardly bulged portion 4, which we find gives added efficiency to the globe provided the diameters of the two outwardly bulged portions are substantially the same.

The point at which the source of light is normally located, is approximately midway between the top and bottom walls of the globe, and the crowns, or extreme outer places of the outwardly bulged portions, are approximately equidistant from said normal source of light point.

The globe is formed by blowing the glass in a mould, and because of its peculiar shape, as above described, we are able to obtain a very thin wall, which makes the globe light, and yet, because of its shape, it is less liable to be broken or cracked from heat or jars. It is to be observed that there are no sharp or abrupt places in the walls, but that the entire wall is composed of reverse

curves. This feature is essential to secure the best results obtainable. The globe is made of translucent material as is customary.

5 One of the advantages of an electric light globe constructed in accordance with the above description, is that its shape permits the wall of the globe to be blown thinner than other shapes. Another advantage is
10 that no hot spots are created in the wall, nor are there any bright spots or dark spots, but the entire wall of the globe diffuses the light evenly. Another advantage is that a lamp of high wattage may be used in the globe.
15 and because of its shape, the intensely bright light is concealed and thoroughly diffused in all directions, thereby greatly increasing the efficiency of the electric light globe. Another advantage is that there is an even
20 flow of light rays because of the peculiar shape given to the walls of the globe. Another advantage is that there are no sharp shadows cast from a light contained in a globe as above described, but the shadows are
25 soft and unobjectionable. Another advantage, as shown by actual test, is that over 91 per cent efficiency is obtained from the source of light, which makes it possible to use electric lamps of less wattage than is
30 ordinarily required to obtain a certain degree of illumination. Another advantage is that the same shape of globe may be maintained for small globes and large globes.

More or less variation of the exact details
35 of construction is possible without departing from the spirit of this invention; we desire, therefore, not to limit ourselves to the exact form of the construction shown and described, but intend, in the following claims,

to point out all of the invention disclosed 40 herein.

We claim as new and desire to secure by Letters Patent:

1. An electric light globe formed of translucent material, the walls of which are relatively thin and of substantially even thickness throughout, and comprising top and bottom walls and a side wall, the top wall sloping outward and downward and the side wall having an annular outwardly bulged upper portion and an annular outwardly bulged lower portion, and there being an annular inwardly bowed portion in said side wall between and merging, along lines that form an obtuse angle, into said outwardly bulged portions, the diameter of said inwardly bowed portion being slightly less than that of the outwardly bulged lower portion. 45 50 55

2. An electric light globe formed of translucent material, the walls of which are relatively thin and of substantially even thickness throughout, and comprising top and bottom walls and a side wall, the top wall sloping outward and downward and the side wall having an annular outwardly bulged upper portion merging into said top wall and an annular outwardly bulged lower portion merging into said bottom wall, and there being an annular inwardly bowed portion in said side wall between and merging, along lines that form an obtuse angle, into said outwardly bulged portions, the diameter of said inwardly bowed portion being slightly less than that of the outwardly 60 65 70 75 bulged lower portion.

MASON A. BAMBOROUGH.
HAROLD A. BAMBOROUGH.
